UNITED STATES PATENT OFFICE.

SAMUEL C. FREY, OF YORK, PENNSYLVANIA.

ELECTRIC-RAILWAY SYSTEM.

No. 887,932.

Specification of Letters Patent. Patented May 19, 1908.

Application filed November 28, 1906. Serial No. 345,461.

To all whom it may concern:

Be it known that I, SAMUEL C. FREY, a citizen of the United States, and resident of York, county of York, State of Pennsylvania, have invented certain new and useful Improvements in Electric-Railway Systems, of which the following is a full and clear specification, reference being had to the accompanying drawings, in which—

10 Figure 1 is a diagram of a portion of a trolley electric railway showing one arrangement of my invention applied thereto; Fig. 2 a similar diagram showing more clearly the relative arrangement of the signal boxes, the 15 signal box numbered 2 and the signal box numbered 1^a being enlarged and opened to better show the circuits; and Figs. 3 and 4 and 5 detail views of a rotary circuit breaker used in each signal box.

20 The object of this invention is to provide a car-stopping and signaling block system especially adapted for single track electric railways of the trolley type and the third rail as well as the underground systems, means being provided whereby each car or train or group of cars or trains as it proceeds pre-empts a section of the road and prevents oncoming or succeeding cars or trains from entering the pre-empted block until it is clear, 25 said means being adapted to supplement the usual signaling devices and to eliminate entirely the human element of danger by practically putting it out of the power of the motorman to pass into a pre-empted block 30 whether or not he desires to do so, thus providing the maximum degree of safety.

I have shown my invention applied to single track roads but it will be obvious that in its broader aspects the invention is applicable to double track roads.

In the preferred form for single track roads my invention consists in dividing up the conductor of the motive current, whether it be a trolley wire or a third rail, into a series of 45 sections E whose opposite ends are split into two branches E' the ends of which branches are adjacent to the two turnout sections E³. These turnout sections of the conductor are normally dead, being isolated from the main 50 conductor by any suitable means, the current being carried around each turnout by a loop E², which loop of course is in such position that it will not be traversed normally by the current-collecting wheel or shoe.

55 A series of signal boxes 1, 1^a, etc., is arranged along one side of the roadbed for

trains going from the right to the left, and a similar but reversed series of signal boxes 2, 2^a, etc., is arranged on the opposite side of the roadbed for trains going from the left to the right. These signal boxes are located respectively at convenient points near the beginning of the respective dead sections of the turnouts, so that each box may be conveniently seen by the motorman as he approaches each turn-out. Each of the dead sections E³ of the conductor is connected through its adjacent signal box to any convenient normally alive part of the main conductor by means of a branch E'. These 70 branch circuits which go to the signal boxes are each adapted to be closed to electrify its connected isolated section E³ by means of an armature B⁴ adapted to be raised when an adjacent magnet B³ is energized, said armature being adapted to be normally locked and held up by means of a depending hooked-armature C⁵, which latter is adapted to be released from armature B⁴ to break circuit E⁵ when a magnet C⁴ is energized. The same 75 arrangement or any equivalent arrangement for making and breaking circuits E⁵ is provided in each of the boxes. At each signal box the live conductor is tapped by a wire E⁶ which supplies, through a resistance coil or 80 rheostat E⁷, the current required for energizing the magnets.

Conveniently arranged in the branch E' which precedes each dead section is arranged a series of five circuit closers which are 90 adapted to be automatically closed in succession as a car approaches the dead section from the main line, and in the branch E' extending from the end of the dead section to the main line are two more circuit closers. 95 These circuit closers may be of any suitable construction and may be arranged to be operated by a trolley wheel or harp or any other suitable part of the car. The series of circuit closers in what may be conveniently 100 termed the lower turn-outs are designated in their order by U, D, F, A, B, C, and G, and the series in each of the upper turn-outs are designated in their order by the same letters and in the same order.

105 The circuits controlled by each of these circuit closers or contacts may be best described by describing what takes place as a car or group of cars traveling in a group traverses the system: Assuming a car to be 110 traveling from the left to the right it first closes U and D, but as these are restoring

devices the effect of passing over them will be better understood after the description of the other circuit closers. In closing F, circuit F' is closed, one branch of which leads 5 to ground by a separate wire, as shown, or through the trolley-pole, and the other branch to adjacent box 2, where it connects with resistance coil E⁷ through magnet F². The energizing of magnet F² attracts hook 10 armature F³ and allows armature F⁴ to fall thereby closing a gap in the outgoing branch of line circuit A' and opening the incoming branch A'' of said circuit. In closing A the circuit A' is closed, one branch of which circuit 15 leads to the adjacent signal box 2, the other branch being connected to ground by a separate wire, as shown, or down through the trolley-pole, as may be preferred. The branch leading to the box passes through the 20 box and on up the roadway and across to E⁷ in box 1^a through branch A''. In passing through box 1^a from E⁷ the current energizes magnet A² thereby lifting armature A³ and breaking one branch of line circuit B' 25 and closing another branch of circuit B' by bringing said armature A³ into contact engagement with hook armature A⁴.

When the car passes over B circuit B' is closed, which brings current from E⁷ in box 30 1^a through armatures A³ and A⁴ and magnet B⁷ and circuit-breaking wheel B⁵ in box 1^a and thence through line portion of circuit B' into box 2 through the incoming branch of circuit B'; in box 2 the current passes 35 through magnets B³ and B², thence to circuit closer B and thence to ground through a separate wire, as shown, or through the trolley-pole and its connections. The energizing of magnet B² sets the semaphore to 40 safety, its normal position being that of danger, and the energizing of magnet B³ closes circuit E⁵ which supplies current to the dead-section E³ and thus allows the car to traverse the same. In passing through box 1^a the 45 current energizes B⁷, thus attracting its armature B⁶ and rotating circuit-breaking wheel B⁵ one notch, said armature B⁶ acting as a pawl for this purpose. The wheel B⁵ is so constructed that when it is thus rotated 50 it breaks the outgoing branch of circuit B'.

As shown, the wheel B⁵ consists of alternating teeth or segments of conducting and non-conducting material, one series being at each face of the wheel, and the conducting 55 teeth or segments at each side being electrically connected but insulated from the conducting teeth or sections at the opposite side of the wheel. One end of circuit B' is connected to this wheel by a depending contact finger B⁸ which rests upon the top of the wheel and is bifurcated so that it will always have one of its branches upon a non-conducting tooth and its other branch upon a conducting tooth of the wheel. The pawl armature B⁶ has its spring pawl portion bearing 60

only on one set of teeth so that it will make contact with first a conducting tooth and then a non-conducting tooth. In the normal conditions of the circuit B', as shown in Fig. 2, the contact finger B⁸ and pawl B⁶ are on conducting teeth at one side of the wheel and thus are electrically connected, but when the wheel is rotated one tooth by a car passing over B the contact finger and the pawl are brought to bear upon non-conducting teeth and the circuit is thus broken at this point. 75

The passage of the motive current through E⁵ energizes a magnet E⁸ in any suitable manner as, for instance, by choking a part 80 of the current out of a normally dead branch of E⁵, by inserting a resistance in said dead branch, as shown in Fig. 2, or by other suitable means. The energizing of E⁸ breaks circuit C' by attracting an armature E⁹ this 85 circuit remaining broken so long as current is passing through E⁵, that is, so long as a car is taking current from E³, for the purpose hereinafter set forth.

Immediately after the car leaves E³, the 90 armature E⁹ is thereby released and permitted to close circuit C' the car passes over circuit closer C which sends an electric impulse from E⁷ in box 2 out through magnets C³, C⁵ and C⁴ to said circuit closer and thence 95 to ground through a separate wire or otherwise. The energizing of C³ attracts C⁴ and thereby releases the signal and allows it to assume its normal danger position. The energizing of C⁴ releases armature B⁴ and 100 allows the same to normally break the supply circuit E⁵ thus restoring E³ to its normally dead state. The energizing of C⁵ attracts armature F⁴ and reengages it with hook armature F³, thus breaking the outgoing 105 branch of A' at F⁴ and simultaneously closing incoming branch A'' of said circuit A'.

If a car be closely following the car whose movements we have been following, as is the case when cars or trains are moving in uncoupled groups on the same block, the second car must be brought on E³ before first car reaches C, as in that way cessation of current through E⁵ will be prevented and consequently the circuit C' will remain open at E⁹ 115 and the passage of the first car over C will have no effect. In this way cars or trains may travel in groups or parties without interfering with each other and in perfect safety, and disastrous arcing by breaking E⁵ 120 while current is flowing therethrough is avoided.

The passage over G closes circuit G' which 125 preferably is entirely metallic. This circuit G' goes to box 2 and one branch is connected to E⁷ and the other branch to outgoing branch of circuit B', so that the closing of the circuit at G sends a current out through line circuit B' and into box 1^a through ingoing branch of B' down through B⁸, B⁵, contact 130

5 finger G^2 and thence through magnet G^3 to ground. This energizes G^3 and raises pawl armature G^4 and thus rotates toothed wheel G^5 one tooth or notch to the left, thus moving contact finger G^6 to the left and breaking circuit D' at K . A contact finger G^2 engaging the lower side of wheel B^5 engages the teeth or segments at the opposite side from the set engaged by armature pawl B^6 , and this finger G^2 is so arranged that whenever 10 B^6 is brought to a non-conducting tooth this finger G^2 will be caused to contact with a conducting tooth on the opposite side of the wheel thus establishing metallic connection 15 with the bifurcated contact finger B^8 .

After traversing the block the car we are following then passes over circuit closer U one branch of whose circuit U' runs to ground in a suitable way and the other branch into 20 box 1^a , through magnet U^2 therein, and thence to the current source E^7 . The energizing of U^2 attracts pawl armature U^3 and rotates wheel G^5 back far enough to the right to cause G^6 to make contact at K and thus 25 close the restoring circuit D' . Then upon passing over D circuit D' is enlivened and magnets D^2 and D^3 are energized, the former attracting armature A^4 and thus allowing A^3 to close the incoming branch of B' and simultaneously break the outgoing branch thereto. 30 The energizing of D^3 causes armature B^6 to turn wheel B^5 another notch and thus bring B^6 into metallic connection with B^8 and thereby close the gap in circuit B' made 35 when the car passed over B . In this way the block just passed over is restored to normal condition and is free to be used by trains going in either direction.

The object of circuit closers G and U and 40 the wheel G^5 is to enable cars or trains to run in groups without inconvenience or danger. If a group of cars be traveling together each car as it passes over G will move wheel G^5 one tooth to the left so that restoring circuit D' cannot be closed at K until as many cars 45 pass over U as previously passed over G , thus eliminating all possibility of rendering circuit B' operative until all the cars of the group or party have passed out of the block.

50 It will thus be seen that in running to the right a car, after restoring through circuit U' and D' the normal conditions in the block behind, will close A' , thus closing one branch of B' at A^4 in box 1^a and also break the other 55 branch of circuit B' at A^3 . It will therefore be impossible for a car approaching box 1^a from the other direction to either effect any change in the conditions in box 1^a or to get current into the dead section E^3 over which it

60 must pass to get beyond the first turn-out. As the car going to the left approaches 1^a the motorman will be apprised of the pre-empting of the next preceding block by the failure of the closing of circuit at B to raise or otherwise set the semaphore arm in 1^a at safety 65

and he will then stop his car before entering upon the dead section E^3 , but should he disregard the signal and pass onto the dead section his car would be stopped for the want of current. Should the car by any mischance 70 become stalled on the dead section it may, after waiting the proper length of time, be moved off the same either by swinging its trolley over onto the connecting portion E^2 of the normally-alive conductor or an attendant 75 may go to the adjacent signal box and manually close E^5 circuit by simply raising armature B^4 . These normally dead sections will usually be made long enough and of the proper grade to bring a car to a standstill 80 by inertia when deprived of current. The sections E' of the main conductor at the beginning of each turnout are desirably made sufficiently long to accommodate two or more cars so that two or more cars may 85 stand on each of these branches until the oncoming car passes off the preceding block. It is obvious that the same operations take effect in the reverse order when a car going to the left approaches each turnout, so that 90 it will be impossible for two cars traveling at a distance apart to get on the same block at one time. It will be observed also that it will be impossible for an oncoming car unless in a group with first car to pass onto a section 95 pre-empted by a preceding car since the passing of a car over B breaks the connected circuit B' and B^5 , thus killing this circuit B' until that car reaches the next succeeding circuit closer D and closes B' at B^5 by energizing magnet D^3 ; and it is obvious that the same operations are effected by the passage of a car over the circuit closers B and D in going in the opposite direction.

It will be observed that if circuit A' is disrupted at any point, the circuit B' will not be closed at A^4 , so that the car coming from the left will not get a clear signal when it reaches B and will therefore be apprised of the fact that either the preceding block is pre-empted 105 or the apparatus is out of order; breakage of circuit B' has a similar effect. Breakage of circuit C' would leave the block open for a following car and also leave a clear signal at box 2 but as this circuit is a short local one 110 the liability of disarrangement is very remote, and anyhow the conductor could by looking back see whether the signal had been set to danger.

The danger of breakage of circuit D' is also 115 infinitesimal but should it break its disruption would obviously bring the system to a standstill until extraordinary means were adopted to repair it.

Having thus fully described my invention, 120 what I claim and desire to secure by Letters Patent, is:—

1. In a system of the type set forth, a series of live conductor sections constituting 125 blocks, each of these sections being divided

into two branches at each turnout, two normally dead conductor sections at each turnout extending between the respective branches, normally open circuits connecting these normally dead sections with an adjacent live conductor, line-circuits in each block, a series of circuit closers in each branch of the live conductor leading to the beginning of the normally dead section, and electrical devices connected to said circuit closers and adapted to successively restore the circuits to normal in the block behind and to render inoperative the line circuits in the block immediately preceding and to close the current supplying section connected to the dead section immediately ahead, and another circuit closer in the branch immediately succeeding each normally dead section, and electrical devices connected with this latter circuit closer for breaking the aforesaid current supplying circuit.

2. In a system of the type set forth, a series of live conductor sections constituting blocks each of these sections being divided into two branches at each turnout, two normally-dead conductor sections at each turnout extending between the respective branches, a normally open circuit connecting each of these normally-dead sections with an adjacent live conductor, line-circuits in each block, a signal near the beginning of each normally dead section of conductor, a series of circuit closers in each branch of the live conductor leading to the beginning of the normally dead section, electrical devices connected to said circuit closers and adapted to restore the circuits to normal in the block behind and to render inoperative the line circuits in the block immediately preceding and to close the current-supplying section connected to the dead section immediately ahead, another circuit-closer, as C, in the branch immediately succeeding each normally dead section, and electrical devices connected with this latter circuit-closer for restoring the signal to danger and breaking the aforesaid current-supplying circuit.

3. In a system of the type set forth, a series of live conductor sections constituting blocks, each of these sections being divided into two branches at each turnout, two normally dead conductor sections at each turnout extending between the respective branches, normally open circuits connecting these normally dead sections with an adjacent live conductor, line-circuits in each block, a series of circuit closers in each branch of the live conductor leading to the beginning of the normally dead section, and electrical devices connected to said circuit closers and adapted to successively restore the circuits to normal in the block behind and to render inoperative the line circuits in the block immediately preceding and to close the current supplying section con-

nected to the dead section immediately ahead, this latter circuit embodying means for immediately breaking itself after closing the current supplying section, and another circuit closer in the branch immediately succeeding each normally dead section, and electrical devices connected with this latter circuit closer for breaking the aforesaid current supplying circuit.

4. In a railway system of the type set forth, a series of normally alive conductor sections constituting blocks, a turnout between the adjacent ends of each section, each turnout embodying a pair of normally dead conductor sections connected to the main current supply by a normally open supply circuit, line-circuits in each block, contact devices near the beginning of each normally dead section and electrical devices connected therewith for restoring the circuits to normal in the block behind and rendering inoperative the line circuits in the block immediately preceding and also closing the current supply connected to the said dead section immediately ahead, and a circuit closer at the end of each dead section and electrical devices connected thereto for breaking the aforesaid current supply circuit.

5. In a railway system of the type set forth, a series of normally alive conductor sections constituting blocks, a turnout between the adjacent ends of each section, each turnout embodying a pair of normally dead conductor sections connected to the main current supply by a normally open supply circuit, line-circuits in each block, contact devices near the beginning of each normally dead section and electrical devices connected therewith for restoring the circuits to normal in the block behind and rendering inoperative the line circuits in the block immediately preceding and also closing the current supply connected to the said dead section immediately ahead, a contact device at the end of each dead section and electrical devices embodying a restoring circuit connected thereto for breaking the aforesaid current supply circuit, and a device in this restoring circuit actuated by the passage of current through said supply circuit for rendering said restoring circuit inoperative while current is passing in said supply circuit.

6. In a system of the type set forth, a series of live conductor sections constituting blocks, each of these sections being divided into two branches at each turnout, two normally dead conductor sections at each turnout extending between the respective branches, normally open circuits connecting these normally dead sections with an adjacent live conductor, line-circuits in each block, a series of circuit closers in each branch of the live conductor leading to the beginning of the normally dead section, and electrical devices connected to said circuit closers and adapted to successively restore the circuits to normal in the block behind and to render inoperative the line circuits in the block immediately preceding and to close the current supplying section

- closer and adapted successively to restore the circuits to normal in the block behind and to render inoperative the line circuits in the block immediately preceding and to 5 close the current supplying section connected to the dead section immediately ahead, this latter circuit embodying a rotary circuit breaker adapted to immediately break this circuit after closing the current 10 supply circuit, and another circuit closer in the branch immediately succeeding said normally dead section and electrical devices connected therewith for breaking the aforesaid current supply circuit, said rotary circuit breaker being restored to normal by the devices connected to one of the circuit closers 15 in the aforesaid series.
7. In a railway car-stopping block-system, a car, a series of live trolley conductors separated at their ends, a normally-dead trolley conductor between the adjacent ends of each two adjacent live conductors, the live conductors being electrically connected around each of these normally dead conductors, 20 means at the end of each block whereby the car as it approaches each of said dead conductors will automatically enliven it and also render inoperative the enlivening means in the preceding block, and means whereby the 25 car on leaving each of the normally dead conductors will automatically restore the same to normal.
8. In a railway car-stopping block-system, a car, a series of live trolley conductors separated at their ends, a normally dead trolley conductor between the adjacent ends of each two adjacent live conductors, the live conductors being electrically connected around each of these normally dead conductors, 30 means at the end of each block whereby the car as it approaches each of said dead conductors will automatically enliven it and also render inoperative the enlivening means in the preceding block, and means whereby the 35 car on leaving each of the normally dead conductors will automatically restore the same to normal, and means for automatically preventing this restoring action while current is passing through the normally dead section.
9. In a railway car-stopping block system of the type set forth, a car, a series of live conductor sections constituting blocks, each of these sections being divided into two branches at each turnout, two normally dead 40 conductor sections at each turnout extending between the respective branches, normally open circuits connecting these normally dead sections with an adjacent live conductor, a series of five circuit closers in the branch 45 leading to each dead section and electrical circuits and devices connected therewith whereby a car approaching the dead section on a branch will automatically restore normal con- 50 ditions in the devices and circuits behind and render inoperative the current supply devices in the block ahead and also close the current supply devices connected to the dead section immediately ahead, and circuit closing devices in the branch leading from each dead section and devices connected thereto for restoring the current supply devices to normal open position. 55
10. In a railway car-stopping block system of the class set forth, a car, a series of live block conductors, a normally dead conductor section between each pair of live conductors, circuit closing means at the end of each block and electrical controlling devices connected thereto whereby a car about to leave a block and enter upon a dead section 60 will automatically restore to normal the controlling devices in the block behind and will render inoperative the controlling devices at the far end of the block immediately ahead and will turn the current into the dead section 65 immediately ahead, and circuit closing devices at the beginning of each block and means connected thereto for restoring the current supply devices to normal, for the purpose set forth. 70
11. In a railway car-stopping block system of the class set forth, a car, a series of normally live conductor sections, a normally dead conductor section between each two adjacent live conductor sections, normally open 75 current supply devices connecting each dead section to the live conductor, circuit closing means at the end of each block section and electrical devices connected thereto for rendering inoperative the controlling devices of 80 the block immediately ahead and closing the current supply to the dead section immediately ahead, these devices embodying a circuit and means for breaking itself, circuit closing devices at the head of each block and 85 operable by a car only on entering a block and electrical devices connected thereto for restoring the current supply of the dead section immediately behind to normal open, and an additional circuit closer at the end of 90 each block and electric devices connected thereto for closing the aforesaid circuit-breaker, these devices including a step-by-step circuit breaker, and means operatively connected thereto whereby each car on entering a block will open this step-by-step breaker one step and on leaving a block will 95 close it one step, for the purpose set forth. 100
